CLAIM

The ornamental design for a transmission end housing, as shown and described herein.

DESCRIPTION

FIG. 1 illustrates a perspective view of a transmission end housing embodying the invention.

FIG. 2 illustrates a front view of the transmission end housing shown in FIG. 1.

FIG. 3 illustrates a rear view of the transmission end housing shown in FIG. 1.

FIG. 4 illustrates a left side view of the transmission end housing shown in FIG. 1.

FIG. 5 illustrates a right side view of the transmission end housing shown in FIG. 1.

FIG. 6 illustrates a top view of the transmission end housing shown in FIG. 1; and,

FIG. 7 illustrates a bottom view of the transmission end housing shown in FIG. 1.

In some embodiments, elements shown in phantom lines do not form any part of the claimed design.
